ELIMINATING RANCIDITY OF GLYCERIDIC OILS

Louis Lang and Ronald J. Baird, Philadelphia, Pa., assignors to The National Sugar Refining Company, New York, N. Y., a corporation of New Jersey

No Drawing. Application April 28, 1955
Serial No. 504,686

6 Claims. (Cl. 260—427)

This invention is that of a method of removing rancidity from liquid glyceride oils. These include those that are liquid at atmospheric temperature as well as those that can be liquefied at elevated temperature at atmospheric pressure or at slight subatmospheric pressure, and without significant decomposition.

The expression "liquid glyceride oils" while including generically both the atmospheric temperature liquid, and the liquefiable, types just mentioned, also embraces both those of vegetable, as well as of animal, origin, and also compatible mixtures of any of them.

The method of the invention involves contacting such a liquid glyceride oil with a quantity of an alkali metal or alkaline earth metal sucrate, starchate, or cellulosate or mixtures of any of them sufficient to remove the rancidity of the oil, and for a time sufficient to do so.

The method of the invention is applicable to remove the oxidative type, as well as the hydrolytic type, of rancidity of the various kinds of liquid glyceride oils.

These glyceride oils include, for example, vegetable oils such as cocoanut, corn, cottonseed, linseed, peanut, rapeseed, soyabean oils, and others; and animal oils whether of marine animals origin such as the fish oils and whale oils and the cod, shark, and whale liver oils, or of land animal origin as tallow and even butter.

The reduction or elimination of rancidity in liquid glyceride oils, by the methods available prior to the invention, involved a number of steps that made the procedures relatively costly. In some cases expensive distillations, under vacuum or with steam, or both are involved. In others, treatment with various chemicals and bleaching operations are included, necessitating also aqueous washing and the problem of adequate drying. The latter still entails the problem of residual water and thus the possibility of hydrolytic rancidity again.

These and other problems and disadvantages are avoided by the simple procedure involved in the method of the invention. According to it, a rancid glyceride oil, having either or both types of rancidity, need only be contacted with the free-flowing alkali metal or alkaline earth metal sucrate, starchate or cellulosate, or mixture of them, and in a quantity sufficient substantially to eliminate the rancidity and for a time sufficient to do so.

That is done very readily by the method of the invention merely by uniformly distributing a comparatively small amount of such metal derivative of the polysaccharide by shaking or stirring in the liquid glyceride oil, or by passing the oil through a bed of the sucrate, starchate or cellulosate, and advantageously at an elevated temperature below that at which significant decomposition of the oil can occur.

The amount of any particular sucrate, starchate, or cellulosate to be used will depend always on the nature and extent of the rancidity of the specific oil to be treated (i. e. "sweetened"). It will regularly be a small amount relative to the oil. Merely as a relatively general indication, it might not often be as much as about five percent, and quite generally might be found to be under

2

about two percent, and quite often could be found more likely to be some part of one percent. Then quite commonly, it could be about one-tenth of one percent, and even less than that. A lower limit cannot be indicated 5 because for the slightest rancidity there would be required possibly merely a minute amount of the treating substance. A slight excess can do no harm. The specific amount required can be indicated readily by the simple test of taking a small sample of the particular oil to be 10 treated and shaking it, preferably at elevated temperature, with one-tenth percent of the selected alkali, or alkaline earth, metal salt of the polysaccharide (namely, the alkali, or alkaline earth, metal sucrate, starchate or cellulosate). Part of the sample then can be filtered and 15 smelled and/or tasted to tell whether or not the rancidity has been eliminated. If it has, the ratio of the sucrate, starchate or cellulosate is adequate. This test can be repeated with a slightly smaller proportion. If the small filtered part of the treated sample should still smell or 20 taste rancid, a slightly further amount should be added and the test continued as described to obtain an indication of the sufficient proportion.

The invention is illustrated by, but not restricted to, the following examples:

25 *Example 1—Oxidative rancidity:* To one hundred pounds of linseed oil having oxidative rancidity, in an open vessel equipped with agitator, there was added one-tenth pound of disodium sucrate (obtained by reacting sodium ethoxide with a solution of sucrose in an amine 30 as in Ronald J. Baird U. S. Patent No. 2,702,249, issued February 15, 1955). The mixture was heated and stirred and held within one hundred twenty-five to one hundred thirty degrees Fahrenheit for one-half hour, and then filtered. The filtrate, treated (sweetened) oil was somewhat 35 lighter in color than the original oil (before treatment) and no longer exhibited any rancid odor and taste.

35 *Example 2—Oxidative and hydrolytic rancidities:* To one hundred pounds of coconut oil having both oxidative and hydrolytic rancidity, in an open vessel equipped 40 with agitator, there was added two-tenths pound of sodium cellulosate (free-running particles called "crumbs," in the field). The mixture was heated and stirred and held within one hundred and twenty-five to one hundred thirty degrees Fahrenheit for one-half hour, and then 45 filtered. The filtered, treated (sweetened) oil was somewhat lighter in color than the original oil (before treatment) and no longer exhibited rancid odor and taste.

The disodium sucrate used in Example 1 can be replaced by disodium sucrate obtained by any other method. Likewise, the disodium sucrate and the sodium cellulosate of these examples can be replaced, in whole or in part, by the equivalent amount of any other alkali metal, as potassium or lithium, or alkaline earth metal, as calcium, barium, strontium or magnesium, sucrate, 55 starchate or cellulosate, or mixtures of any of these. As seen from Baird Patent 2,702,249, the salt of the polysaccharide is the non-carboxylate type.

The linseed oil of Example 1 can be replaced by any other glyceride oil having oxidative rancidity and of 60 vegetable or animal origin. So also, the coconut oil of Example 2 can be replaced by any other glyceride oil having both oxidative and hydrolytic rancidity and also of vegetable or animal origin.

65 In some operations, it may be found convenient to make the contact between the oil and the rancidity-removing agent by percolating the oil, preferably at elevated temperature, through a bed, of suitable size and depth of the selected rancidity-removing agent of the invention, to enable sufficient time of contact between the oil 70 and the rancidity-removing agent to remove the rancidity. If desired, the bed can be made of considerable depth to be able to handle a relatively extensive volume of the

rancid oil to be treated. In some such case, it can be advantageous to have the vessel holding the bed of the agent jacketted to permit controlled heating.

In any event, the invention is not founded in teaching any particular range of proportions between the rancidity-removing agent and the rancid oil "to be sweetened" or in the rate of flow of the oil percolated through a bed of the agent or in the particular depth of the bed. The fundamental feature of the invention is the discovery that these alkali, or alkaline earth, metal sucrates, starchates or cellulosates, or mixtures of any of them, are effective to remove the indicated rancidity from the glyceride oils, and by so simple a procedure.

While the invention has been illustrated by detailed description of certain specific embodiments of it, it is understood that various modifications and substitutions can be made in various features of any of them within the scope of the appended claims which are intended also to embrace equivalents of the various embodiments.

What is claimed is:

1. The method of eliminating rancidity of a glyceride oil, which method comprises contacting the rancid glyceride oil with a quantity of a rancidity-removing agent from the class consisting of an alkali metal sucrate, an alkaline earth metal sucrate, and alkali metal starchate, an alkaline earth metal starchate, an alkali metal cellulosate, an alkaline earth cellulosate, and a mixture of any of them, sufficient to eliminate the rancidity and

25

15

20

25

for a time sufficient to do so; and separating the rancidity-removing agent from the thus treated oil.

2. The method as claimed in claim 1, wherein the rancidity-removing agent is added to the rancid oil and the resulting mixture is agitated.

3. The method as claimed in claim 2, wherein the mixture is heated while the rancidity-removing agent is in contact with the oil and at a temperature below that at which decomposition of the oil occurs, and when the contact has continued long enough for the rancidity to be removed, filtering the mixture to remove the agent.

4. The method as claimed in claim 3, wherein the temperature to which the mixture is heated does not exceed one hundred and sixty degrees Fahrenheit.

5. The method as claimed in claim 1, wherein the quantity of the rancidity-removing agent is under about five percent by weight of the rancid oil.

6. The method as claimed in claim 4, wherein the quantity of the rancidity-removing agent is under about one percent of the rancid oil.
